GRINDING MACHINE

Arnold R. Johnson, Underwood, N. Dak.

Application March 31, 1938, Serial No. 199,264

1 Claim. (Cl. 51—3)

This invention relates to grinding machines especially adapted for sharpening razors, knives, shears and other types of cutlery and has for the primary object the provision of an inexpensive, portable power driven device of this character whereby a person with ease may properly sharpen cutlery through the use of an endless belt-like grinder and a grinding wheel, the device being so constructed that the grinding operation may be carried on without interference from improperly positioned parts and with economy, the bearings, power means and other parts of the device being protected from the grindings and adjustable rests being provided so that the cutlery may be properly supported relative to the grinder during the sharpening operation.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation, partly in section, illustrating a grinding machine constructed in accordance with my invention.

Figure 2 is an end elevation, partly in section, illustrating the same.

Figure 3 is a transverse sectional view taken on line 3—3 of Figure 1.

Figure 4 is a fragmentary top plan view illustrating the device.

Figure 5 is a disrupted front elevation showing a tightener used in conjunction with the endless belt type grinder.

Figure 6 is a perspective view illustrating one of the members of a rest.

Figure 7 is a detail sectional view showing the mounting of said member in a standard of the device.

Figure 8 is a side elevation illustrating a modification of my invention.

Figure 9 is a fragmentary perspective view of a tool rest showing an adjustable support thereon.

Referring in detail to the drawings, the numeral 1 indicates a base on which is mounted an electric motor 2 equipped with a belt pulley 3 capable of adjustment endwise of the power shaft 4 of the electric motor. The electric motor is located adjacent one end of the base and adjacent the opposite end of the base are pedestals or standards 5 having journals 6 to rotatably support a shaft 7 on which is secured a plurality

of closely related belt pulleys 8 of different sizes. An endless belt 9 is employed for connecting the pulley 3 to any one of the pulleys 8 so that the shaft 7 may be driven at different rates of speed by the electric motor. It is preferable that the pulleys 8 be of the peripheral grooved type.

One end of the shaft 7 has secured thereon a grinding wheel 9' having associated therewith a rest 10 on which cutlery may be positioned to be brought in contact with the periphery of the grinding wheel. The rest 10 is carried by a support 11 mounted on the standards or pedestals 5 and which includes separable sections adjustably connected by a bolt 12 which will permit the rest 10 to be adjusted towards and from the grinding wheel 9' and also to be adjusted towards and from either peripheral edge of the grinding wheel. The rest 10 also may be adjusted vertically and held in the vertical adjusted position by a set screw 11'. The journals 6 have suitable lubricating cups to maintain the journals and the shaft thoroughly lubricated at all times.

The other end of the shaft 7 has mounted thereon a pulley 13 over which is trained an endless belt type grinding element 14, the latter also being trained over a pulley 15 journaled on a standard 16 carried by the base 1. The endless grinding element 14 may be constructed of any material suitable for the purpose and is engaged by a tightener 17 mounted on the base 1. The tightener 17 includes a bracket 18 secured on the base and having a vertically arranged portion to which a member 19 is adjustably secured. The member 19 has a flanged pulley 20 journaled thereon contacting with the lower run of the endless grinding element 14. Through the adjustment of the member 19 on the bracket 18 the endless grinding element may have the slack therein increased and decreased as described.

The standard 16 has a cutlery rest 21 adjustably mounted thereon. The rest 21 includes a table 22, a vertical member 23 secured to said table and adjustably mounted in a head 24 of a member 25. The member 25 is adjustably mounted in the standard 16. The members 23 and 25 being adjustable relative to each other permits the table 22 to be adjusted vertically and the member 25 being adjustable on the standard 16 permits the table 22 to be adjusted towards and from the pulley 15. The table 22 is so positioned that a razor, knife or the like supported thereon may be brought in contact with the grinding element 14 as the upper run leaves the pulley 15. This arrangement permits the operator to efficiently and accurately grind the knife or razor.

The table 22 has slidably mounted thereon a support 21' and which may be adjusted on said table through the rotation of a finger piece 22' forming an integral part of a screw threaded stem 23' having threaded engagement with a screw threaded opening of an ear 24' formed on the support 21'. The support 21' may be adjusted toward and from the endless grinding element 14 when the latter passes over the pulley 15. The purpose of the support 21' is to maintain a razor at a proper inclination to the endless grinding element 14 where the latter leaves the pulley 15 to assure efficient grinding of the cutting edge of the razor, the non-cutting edge lying on the rest 21. To grind a razor properly, the grinding operation is from the non-cutting edge toward the cutting edge and throughout the length and width of the razor. To accomplish this the rest 21 is lowered so that when the razor is positioned with the non-cutting edge thereof on the support 21' the endless grinding element 14 as it leaves the pulley 15 will be contacting the razor adjacent to the non-cutting edge and as the grinding operation continues the support 21' is moved toward the element 14 thus bringing about the grinding of the razor towards the cutting edge. The diameter of the pulley 15 must be such that it will present a proper curvature to the endless grinding element 14 as it leaves said pulley 15 to fit in the hollow face of the razor between the cutting edge and the non-cutting edge. By gradually grinding the razor from the non-cutting edge toward the cutting edge brings about a proper sharpening of the cutting edge so that very little honing is required of the cutting edge in order that the cutting edge become extremely keen or sharp. The rest 21 being of the construction described will assure against the slipping of the razor during the grinding operation and consequently obviate possibility of marring or nicking the cutting edge. The member 25 being provided with a flat face engaged by the set bolt 28' will prevent the member 25 from wobbling in its support, consequently maintaining the table 22 level and in proper position with respect to the endless cutting element as it leaves the pulley 15. It will also be noted that the edge of the table 22 adjacent the pulley 15 is cut away to permit straddling of the pulley and the endless grinding element by the table and which will permit the support 21' to be adjusted as close to the pulley 15 as desired. Through this arrangement of table 22 the support 21' has a comparatively wide range of adjustment toward and from the pulley 15 and the endless grinding element as it leaves said pulley 15 so that razors of various widths can be accommodated and properly ground.

Shears, scissors or the like are ground on the grinding wheel, 9', they being supported by the rest 10 during the grinding operation.

A guard 26 is mounted on the pedestal of the electric motor and protects the latter from grindings from the grinding elements. A guard 27 is carried by the standards 5 for protecting the journals from grindings. Also a felt washer or packing 27' cooperates with the guard 27 in protecting one of the journals 6 from grindings which may pass from the endless grinding ele-

ment 14 as the latter passes over the pulley 13.

The pulley 3 being adjustable endwise of the shaft 4 of the electric motor permits aligning of the drive belt at all times regardless with what pulley of the group of pulleys 8 the belt is in engagement with.

If desired, a machine of this kind may be constructed minus the grinding wheel 9' and if so a standard 28 is employed in lieu of the standard 5 and has journaled thereon a shaft 29 carrying a group of belt pulleys 30 protected by a guard 31. The shaft 29 has secured thereto the pulley 13. It is preferable that the pulley 15 be constructed of some yieldable material such as rubber which will present a cushioning effect or give when sharpening a razor, knife or the like so that a smoother grinding will be had on the cutlery during the grinding operation.

The rest 10 which is especially shaped for supporting blades of scissors or shears for grinding on the grinding wheel 9' has a portion thereof reduced and provided with flattened faces and disposed angularly to its post. The upper edge of the angularly related end is designated by the character 19' and is shown as having a bevel thereto so that when a blade of scissors or shears is positioned thereon the cutting edge of said blade will be presented properly to the grinding face of the grinding wheel 9' so that said cutting edge will be sharpened with a proper bevel. In sharpening the blade of the scissors or shears the handle end is first engaged with the grinding wheel 9' with the grinding operation proceeding toward the free end of the blade. A rest 10 of the character described will prevent the blade of the scissors or shears from slipping off of the rest and support the blade at a proper angle to the grinding face of the grinding wheel 9' so that an efficient cutting edge will be ground on said blade.

Referring to the tightener 17 the upstanding portion of the bracket 18 thereof is provided with a lug 18' which operates in a slot 20' to aid in preventing the member 19 from moving out of vertical alignment with the vertical portion of the bracket 18 but which will permit the member 19 to be easily adjusted vertically on the vertical portion of the bracket 18 when the nut on the bolt joining these parts has been backed up.

What is claimed is:

In a grinding device, a standard, a grinding element rotatably mounted on said standard, a table disposed adjacent said standard and formed with spaced arms receiving therebetween said element and adapted to support a work-piece thereon for engagement of the cutting edge of said work-piece with said element, a support on said table adapted to engage a non-cutting edge of said work-piece, adjustable means connecting said table to said standard to permit vertical and horizontal adjustment of the table with respect to said element, and a member carried by said table and threadededly connected to said support for adjusting the latter relative to said element whereby said work-piece is moved by said support towards said element to effect grinding of said work-piece in a direction towards said cutting edge.

ARNOLD R. JOHNSON.
